UNITED STATES PATENT OFFICE.

HENRY F. CRANDALL, OF RACINE, WISCONSIN.

SAFETY-RAZOR.

1,117,953.

Specification of Letters Patent. Patented Nov. 17, 1914.

Application filed September 8, 1913. Serial No. 788,510.

To all whom it may concern:

Be it known that I, HENRY F. CRANDALL, a citizen of the United States, residing at Racine, in the county of Racine and State of Wisconsin, have invented certain new and useful Improvements in Safety-Razors, of which the following is a specification.

My invention relates to safety razors, and has for its object to provide an exceedingly simple, cheap and effective safety razor.

To these ends it consists in the various features of construction and arrangement of parts adapted to coöperate in a manner substantially as hereinafter pointed out.

Referring to the accompanying drawings, wherein I have illustrated the preferred embodiment of my invention—Figure 1 is a top plan view of the holder, showing the blade in position as inserted therein; Fig. 2 is a side elevation of Fig. 1; Fig. 3 is a view showing a blank from which the holder is formed; Fig. 4 is a top plan view of a similar holder but formed from material having a different cross section; Fig. 5 is a bottom view of Fig. 4, partly in perspective; Fig. 6 is a side elevation of Fig. 4; and Fig. 7 is a cross section of Fig. 5 along line A—B.

One of the objects of my invention is to make a complete safety razor which shall comprise only two parts; that is, a holder for the blade and a separable razor blade, and these shall be adapted to correlate to each other so that the blade may be easily placed and held in operative position on the holder and detached therefrom, and when assembled the parts being in the best position for practical use. Furthermore, I prefer that the resiliency of the side members of the holder alone will retain the two parts of the razor in operative position.

The holder 1, which is preferably made of a single piece of sheet steel cut in the form shown in Fig. 3, has a body portion 2 and curved reduced end portions 3 terminating in angularly disposed head portions 4, having inwardly arranged comb members 5. The blank is then turned into a concavo-convex form at its central portion that is gradually increased toward the end of the blank in a manner to reduce the diameter as it approaches the curved portions 3, resulting in a gradually tapering form having straight converging edges. The next step consists in bending it at its middle into semi-circular form, bringing the ends of the body portion close together, with the curved and

angular extremities disposed laterally and in the same plane. The heads 4 are then folded inward in a manner to bring the end portions of the comb members 5 in close proximity, their bodies in parallel relation and with the head portions 4 at approximately a 45° angle with the body of the holder; the comb members 5 being given a slight curve upward toward the holder, as shown in Fig. 2, and the line of fold milled or otherwise finished in a manner to operatively receive the ends of a blade 6, as shown in Fig. 1. The side members of the holder are knurled for the purpose of affording a better grip for the user.

All that is necessary to insert or remove a blade is to spring the two side members of the holder apart by a pressure of the finger or thumb between them in front of the neck of the holder, the resiliency of the side members being sufficient to securely hold the blade in operative position and permit ready removal thereof.

In Figs. 4, 5, 6 and 7 I have shown substantially the same form of blade holder made out of heavy wire, the handle portion having a semi-circular head 7, forwardly converging sides 8 that terminate in laterally curved portions 9 that terminate in blade holding, or head members 10, that are turned downward and toward the body of the holder at approximately an angle of 45°, the extremities thereof being turned inward in parallel relation and at right angles with the longitudinal center of the holder and milled to form a guard comb 11 for the edge of a blade, the head members 10 being provided with grooves 12 for the reception of a blade 13, as shown in Fig. 7.

In operation the blades are released or secured in the same way as in the form described first. Having shown both preferred and modified forms of my invention, I do not wish to confine it closely to either embodiment, as various minor changes may be made therein without departing from the spirit of my invention.

What I claim as my invention, and desire to secure by Letters Patent, is:

1. A safety razor blade holder formed of a single piece of metal, having forwardly converging resilient side members terminating in outwardly turned diverging portions disposed at an angle with each other and having downwardly turned heads terminat-

ing in inwardly turned separated comb
members disposed in parallel relation, said
heads being freely movable bodily at all
times toward or from each other in parallel
relation in a manner to receive a blade and
secure it in operative position by means of
pressure distributed equally across its oppo-
site ends.

2. A safety razor blade holder formed of
10 a single piece of metal, having forwardly
converging resilient side members terminat-
ing in outwardly turned diverging portions
disposed at an angle with each other and
having downwardly turned heads disposed

at an angle of approximately 45° with the 15
body of the holder and terminating in in-
wardly turned separated comb members dis-
posed parallel with each other, said heads
being freely movable bodily at all times to-
ward or from each other in parallel rela- 20
tion in a manner to receive a blade and
secure it in operative position by means of
pressure distributed equally across its oppo-
site ends.

HENRY F. CRANDALL.
